George A. Field

United States Patent Office.

GEORGE A. FIELD, OF TAUNTON, MASSACHUSETTS, ASSIGNOR TO THE
ALBERT FIELD TACK COMPANY, OF SAME PLACE.

Design No. 3,883, dated March 8, 1870.

DESIGN FOR TACK-HEAD.

The Schedule referred to in these Letters Patent and making part of the same.

To all whom it may concern:

Be it known that I, GEORGE A. FIELD, of Taunton, in the county of Bristol, and State of Massachusetts, have invented and produced a new and original Design for Tack-Heads, of which the following is a specification, reference being had to the accompanying drawing forming part thereof, and in which—

Figure 1 represents a top view, and

Figure 2, a side view of the tack with my improved design on its head.

My design for tack-heads consists of a raised star, *a*, of pentagonal shape, on the top of the head *b* of the tack, over, or in line with the shank *c* of the latter.

I claim as my invention—

The design for tack-heads as herein shown.

GEORGE A. FIELD.
